UNITED STATES PATENT OFFICE.

LEONARD D. NILSON, OF WAYZATA, MINNESOTA, ASSIGNOR TO MARQUETTE MANUFACTURING COMPANY, OF ST. PAUL, MINNESOTA, A CORPORATION OF MINNESOTA.

CRANE.

Application filed November 2, 1925. Serial No. 66,303.

This invention relates to new and useful improvements in cranes, generally, and more particularly relates to cranes of the portable type adapted to be mounted upon the rear portion of an automobile truck or other vehicle to be used as a wrecking crane for towing or lifting wrecked automobiles, or other vehicles.

An object of the invention is to provide a crane having the guide sheave at the upper end thereof so mounted in a swivel head that the pull chain or cable passing thereover may be secured to a load from any angle regardless of the position of the crane.

A further object of the invention is to provide a wrecking crane having the upper guide sheave mounted in a swivel head so constructed that the pull chain or cable may be readily disconnected therefrom without disconnecting the chain from the winding drum or load, thereby permitting the crane to be used as a winch and a direct pull on the load affected which is desirable when towing or pulling a wrecked automobile or other load up over an embankment, or out of a mud hole or ditch.

A further object is to provide a crane having the winding drum mounted directly up on the drive shaft and adapted to be operatively connected therewith by means of an epicyclic gear mechanism preferably mounted at one end of the drum, whereby a relatively high speed ratio may be obtained between the winding drum and the driving shaft, thereby greatly increasing the leverage of pull upon the chain or cable, said mechanism also being provided with means for positively locking the drum to the shaft for rotation as a unit therewith, a desirable feature when winding up the chain or unwinding it.

The particular object of the invention, therefore, is to provide a wrecking crane of simple and inexpensive construction which may be used either for lifting or as a winch, and having a boom adjustably mounted upon its supporting members so that any desired degree of overhang of the lifting chain may be obtained.

Other objects of the invention will appear from the following description and the accompanying drawings and will be pointed out in the annexed claims.

In the drawings there has been disclosed a

structure designed to carry out the various objects of the invention, but it is to be understood that the invention is not confined to the exact features shown, as various changes may be made within the scope of the claims which follow.

In the accompanying drawings forming part of this specification;

Figure 1 is a perspective view of the improved crane;

Figure 2 is an enlarged detail sectional view showing the general construction of the winding drum and the means for operatively connecting it to the drive shaft;

Figure 3 is a vertical sectional view on the line 3—3 of Figure 2;

Figure 4 is a detail sectional view showing the means provided for locking the winding drum to the drive shaft for rotation as a unit therewith;

Figure 5 is a detail sectional view on the line 5—5 of Figure 2;

Figure 6 is an enlarged detail sectional view showing the general construction of the swivel head at the upper end of the boom;

Figure 7 is a detail sectional view on the line 7—7 of Figure 6; and

Figure 8 is a detail sectional view showing how the lifting chain or cable is disconnected from the guide sheave at the upper end of the boom.

The novel crane shown in this invention comprises lower supporting members 11 having upright members 12 of the boom pivotally connected thereto by such means as the bolts 13. Adjustable braces 14 connect the upper ends of the boom uprights 12 with the opposite ends of the supporting members 11. Each brace 14 is preferably made of two sections having a plurality of apertures 15 through which bolts 16 are inserted for securing together the two sections. By this novel construction, the angle of the boom may be relatively adjusted to obtain the desired degree of overhang of the lifting chain or cable. The lower ends of the boom uprights 12 are tied together by means of a cross member 17 and the supporting members 11 are likewise spaced apart by a suitable spacing member 18 interposed therebetween and having a tie bolt or rod 19 securing together the braces 14, supporting members 11 and the spacing member 18. Suitable apertures 21 are also provided in

the horizontal webs of the supporting members 11 to provide means for securing the crane, as a whole, to the floor or bottom 22 of the truck or other vehicle body as shown in Figure 1.

An important feature of this invention resides in the novel construction of the swivel head provided in the upper end of the boom for supporting the guide sheave 23 over which the lifting chain or cable 20 passes when the crane is used for lifting a load. This novel head comprises a forked socket member 24 secured to the upper end portion of the boom uprights 12 by suitable means such as bolts or screws 25 (see Figure 7). Spaced lugs 26 are formed on the socket member 24 to receive the upper ends of the braces 14 secured thereto by a bolt 27. The sheave 23 is mounted in a forked member 28 having a cylindrical portion 29 rotatably mounted in the socket member or head 24. The forked end of the member 28 is offset as shown in the drawings, so that the chain depending therefrom will clear the boom when the crane is being used for lifting a load and when the chain is in the position shown in Figure 1. One side of the cylindrical portion 29 of the forked member 28 is provided with an elongated opening 32 extending the full length thereof adapted to be moved into alignment with a similar opening or slot 33 provided in the head 24 between a pair of spaced lugs 34. The lugs 34 are apertured to receive a bolt 35 for securing the clevis 36 thereto. A suitable hook 37 is secured to the end of the chain 24 to provide means for detachably securing the end of the chain to the clevis 36 or for connecting the chain to a load when the crane is being used as a winch and a direct pull on the load is desired. A chain guide 38 is mounted upon the forked member 28 to guide the chain onto the sheave 23 when the crane is lifting a load, should the load be slightly out of alignment with the sheave 23. This guide may be supported by a pin or bolt 39 upon which the sheave 23 is mounted.

By means of the elongated openings 32 and 33 in the head 24 and the cylindrical end portion 29, the chain may be readily disconnected from the upper end of the boom without the use of tools, when it is desired to obtain a direct pull from the drum to the load in pulling a wrecked car or other load over an embankment or out of a mudhole or ditch. To disconnect the chain from the sheave 23 and head 24, the forked member 28 will be rotated from the position shown in Figures 1 and 6, to that shown in Figure 8 and then the elongated openings or slots 32 and 33 will be in alignment or registration with each other so that by removing the pin 35 the chain may be removed from the head through the aligned slots 32 and 33

as shown in Figure 7. The guide 28 is also provided on one side with a slot 41 so that the chain may be removed therefrom. The relative positions of the slots 32 and 33 are such that when the forked member 28 is in normal position, as shown in Figures 1, 6 and 7, they will be substantially 180° apart, thereby providing a cylindrical guide through the head for the chain and at the same time a swivel support for the sheave 23 to permit the sheave to adapt itself to any angularity or side pull of the chain with relation to the truck upon which the crane is mounted. Referring particularly to Figure 6, it will be noted that the sheave 23 at the upper end of the boom is arranged to cause the chain section between it and the drum to travel substantially in axial alignment with the axis of the swivel head, thereby permitting the sheave to readily adjust itself to any angularity or side pull of the chain when pulling or lifting a load. As indicated by dotted lines in Figure 1, the cable having been separated from the sheave by moving it laterally through the slotted openings in the supports of the sheave, can be extended directly to the load for a direct pull from the drum thereon, the load being usually a car or truck in a ditch or one stalled in a mudhole. The crane is, therefore, adapted for lifting purposes when the boom is utilized and may be quickly converted into a device for use as a winch or windlass when a direct pull is to be applied to the load. When the crane is used for lifting, as shown in Figure 1, a tackle block 42 is preferably mounted upon the chain to increase the leverage or pull upon the load.

A winding drum 43 is rotatably mounted upon a drive shaft 44, having an operating crank 40 secured to one end thereof. This shaft is mounted in suitable anti-friction bearings 45 and 46 secured to the boom uprights 12 by brackets 47. These bearings are preferably mounted in the brackets 47 in such a manner as to be self-aligning, thereby preventing any possibility of the shaft binding in the bearings as a result of yielding of the boom and frame structure under a heavy load. The drum 43 is also mounted upon the shaft in suitable roller bearings 48 to minimize friction.

In structures of this type, it is desirable to provide means for increasing the leverage or pull upon the cable or chain so that extremely heavy loads may be pulled or lifted with a minimum amount of exertion on the part of the operator, cranes of this type being usually hand-operated. Means are therefore provided for effecting a relatively high speed ratio between the winding drum and the drive shaft 44 which is so constructed that it may be readily rendered inoperative and the drum rotated directly with the shaft. To effect such relatively high

speed ratio between the winding drum 43 and the shaft 44, an epicyclic or external gear 49 is mounted upon an eccentric 51 secured to the shaft 44 by a key 52. Suitable anti-friction rollers 53 are preferably interposed between the bore of the epicyclic gear 49 and the hub of the eccentric 51 to reduce friction. The gear 49 is adapted to mesh with an internal gear 54 secured to one end of the winding drum 43 as particularly shown in Figures 2 and 4. The gear 49 is also of a relatively smaller diameter than the internal gear 54, as shown in Figures 2 and 3, which diameter is dependent upon the size of the eccentric and the desired speed ratio required between the drum 43 and the drive shaft 44. When it is desired to rotate the drum 43 at a relatively slow speed, as in pulling a heavy load, the gear 49 will be locked against relative rotation so that as the shaft, and therefore the eccentric 51, is rotated, the gear 49 will have an epicyclic motion as a result of being mounted upon the eccentric and being locked against rotation. Such epicyclic motion of the gear 49 will cause the drum 43 to be rotated a fraction of a revolution dependent upon the difference between the number of teeth in the epicyclic gear 49 and the internal gear 54. For instance, should the epicyclic gear 49 have 42 teeth and the internal gear have 44 teeth, then for each revolution of the drive shaft 44, the drum 43 would be rotated a fraction of a revolution equal to the spacing between two of its teeth.

Means are therefore provided for locking the gear 49 against rotation to effect such relative rotation of the drum with respect to the shaft. Such means preferably consists of a latch 55 pivotally mounted in the gear 49 and having a lug 56 between which and a portion of the gear 49 a compression spring 57 is mounted adapted to normally move the latch 55 into locking engagement with one of a series of notches 58 provided in an annular flange 59 integrally formed preferably with one end of the eccentric 51. A hand lever 61 is provided on the latch 55 whereby the latch may be manually moved out of locking engagement with the flange 59. A stud 62, having a flanged head 63, is mounted in one side of a cover plate 64 which preferably has a central hub 65 integrally formed with the bearing 46 supporting one end of the drive shaft 44. A roller 60 is mounted upon the stud 62 and adapted to be engaged by the hand lever 61 when the external gear 49 is locked against rotation. The cover 64 is suitably secured to the adjacent upright 12 of the boom and cooperates with the internal gear 54 to provide a closure for the drive mechanism of the drum (see Figure 2). A hand grip 66 is secured to the opposite end of the stud 62 for rotating the stud and the head 63. When the latch 55 is moved out of locking engagement with the flange 59 of the eccentric and the lever 61 is moved into engagement with the roller 60 on the stud 62, the epicyclic gear 49 will be locked against rotation, thereby causing the drum 43 to rotate at a relatively slow speed when the shaft 44 is rotated. Suitable lugs 67 are preferably provided in the cover plate 64 between which the lever 61 is located when in the position above described. These lugs and the roller 60 function to positively lock the latch, and therefore the gear 49, against rotation when the drum is operating at a relatively slow speed. When the latch is thus positioned and the shaft 44 is being rotated, there will be a slight reciprocal movement of the hand lever 61 against the roller 60 caused by the epicyclic movement of the external gear 49. A spring bolt 68 is provided in the hand grip 66 to lock the stud 62 in its adjusted positions. The flanged head 63 of the stud 62 is preferably cut away on one side as shown at 69 in Figure 3, so that when the stud is rotated substantially a quarter of a revolution (or until the cut-away portion 69 is substantially parallel with the hand lever 61) the latter will be moved to the position shown in Figure 4 by the action of the spring 57; thereby locking the external gear 49 to the eccentric with the result that the drum 43 will rotate directly with the shaft, there being no relative movement between the gears 49 and 54.

A ratchet 71 is preferably provided on the outer face of the internal gear 54 adapted to be engaged by a spring bolt 72 as shown in Figures 2 and 5. The purpose of this ratchet device is to prevent the drum from unwinding when lifting or pulling a load, especially if the chain is pulling directly from the drum. A compression spring 73 is coiled about the reduced portion 74 of the bolt 72 and is seated in a bore provided in a hub 75 in the cover plate 64. This spring functions to normally move the bolt 72 into engagement with the ratchet 71. A pin 76 is mounted in the reduced portion 74 of the bolt adapted to be received in a slot 77 provided in the hub 75 of the cover plate 64. This pin functions to retain the bolt 72 in proper alignment with the ratchet 71 and also to retain the bolt in inoperative position when unwinding the drum as indicated by dotted lines in Figure 2. The foregoing described mechanism provides a means for internally locking the external gear so that the drive and strain thereon will be outward and applied to the gear near the center thereof, and there will be no peripheral strain on the gear by the application of the lock. I thus eliminate to a considerable degree the danger of breakage.

In the operation of this novel crane, the chain 20 will normally be in the position

shown in Figure 1, the position most frequently employed in lifting or towing wrecked cars. When it is desired to secure the chain to a load, the handle 61 of the latch 55 will be released from the flanged head 63 of the bolt 62, and the bolt 72 disengaged from the teeth 71, thereby permitting the drum to be rotated at a relatively high rate of speed, as it will rotate directly with the drive shaft 44. As soon as the chain has been secured to the load, the slack in the chain may be taken up by first rotating the drum as a unit with the shaft, until it becomes taut and the load becomes too great for the operator to lift or pull without the employment of an increased leverage between the shaft and the drum. The lever 61 on the latch 55 may then be moved from the position shown in Figure 4 to that shown in Figure 2, thereby locking the external gear 49 against relative rotation, and causing it to have an epicyclic movement as a result of its eccentric mounting upon the shaft 44. Such movement of the gear 49 will cause the drum 43 to be rotated in the same direction at a relatively slower speed. By the employment of the ratchet 71 and spring bolt 72, the load may be suspended in midair, or, at any desired point without danger of accidentally becoming disconnected from the crane.

Should it be desired to operate the chain 24 directly from the drum as when pulling or towing an automobile or other load up over an embankment, then the chain may readily be disconnected from the swivel head at the upper end of the boom as hereinbefore described, after which it may be connected directly to the load and a direct pull exerted thereon. (See dotted lines, Figure 2.) This novel crane is therefore well adapted for use in connection with garages and repair shops for towing in wrecked cars, trucks, and the like. It may also be used for pulling vehicles out of the mud or a ditch and for various other purposes without departing from the invention.

I claim as my invention:

1. A winding apparatus comprising a drum, an internal gear thereon, a drive shaft, an external gear arranged to mesh with the teeth of said internal gear, means for operating said external gear from said shaft, and means internally arranged with respect to said external gear for locking it to said driving means.

2. A winding apparatus comprising in combination, a drum, an internal gear secured thereto, an eccentrically and loosely mounted external gear constantly in mesh with said internal gear, and a lever mechanism within said external gear adapted to lock it for transmission of power from said external gear to said internal gear.

3. A winding apparatus comprising in

combination, a drum, having an internal gear secured thereto, a shaft for said drum, an eccentric secured to said shaft, an external gear loosely mounted upon said eccentric and constantly meshing with said internal gear, a lever mechanism tending normally to lock said external gear to said eccentric for rotation as a unit therewith, and means for holding said lever mechanism out of engagement with said eccentric to prevent the rotation of said external gear, thereby causing said drum to be rotated at a relatively slower speed than said shaft.

4. A winding apparatus comprising in combination, a shaft, a drum rotatably mounted thereon, an internal gear secured to said drum, an eccentric having a plurality of notches secured to said shaft, an external gear loosely mounted on said eccentric, a locking member on said external gear adapted to engage said notches and a stop adapted to engage said locking member to hold said external gear against rotation when said shaft is rotated, thereby causing said drum to be rotated at a relatively slower speed than said shaft.

5. A winding apparatus comprising in combination a drive shaft, a winding drum rotatably mounted thereon, an internal gear on said drum, an external gear in mesh therewith, an eccentric supporting said external gear, a pivoted lever member mounted on said external gear, a stationary stop, said lever member having an arm adapted to be moved into engagement with said stop to cause said external gear to impart a relatively slow rotary motion to said internal gear when said shaft is rotated, said arm when moved out of engagement with said stationary stop and said lever member is engaged with said eccentric locking said winding drum to said drive shaft for rotation as a unit therewith.

6. A winding apparatus comprising in combination a drive shaft, a winding drum rotatably mounted thereon, a supporting means for said shaft, an internal gear on one end of said drum, an eccentric having a plurality of notches secured to said shaft, an external gear mounted for relative rotation thereon, and adapted to be in constant mesh with said internal gear, a lever member mounted on said external gear, and adapted to engage said notches to lock said external gear to said eccentric to cause the mechanism to be rotated as a unit, a stop upon said supporting means for engaging said lever member to lock said external gear against rotation, thereby causing said external gear to move bodily around the axis of said shaft for transmitting a relatively slow rotary motion to said internal gear and said winding drum.

7. A support, a shaft journaled therein, a drum upon the shaft having an internal

gear, an external gear meshing with the internal gear, said external gear being eccentrically mounted upon the shaft, and a latch carried by the external gear, and alternately engageable with the shaft and support for the purpose set forth.

8. A support, a shaft journaled therein, a drum upon the shaft having an internal gear, an external gear meshing with the internal gear, said external gear being eccentrically mounted upon the shaft, and a latch carried by the external gear, and alternately engageable with the shaft and support for the purpose set forth, said latch being within the external gear.

9. A support, a shaft journaled therein, a drum upon the shaft having an internal gear, an external gear meshing with the internal gear, said external gear being eccentrically mounted upon the shaft, and a latch carried by the external gear, and alternately engageable with the shaft and support for the purpose set forth, said latch being within the external gear and being protectingly 25 closed between said gear and said support.

10. A support, a shaft journaled therein, a drum upon the shaft having an internal gear, an external gear meshing with the in-

ternal gear, said external gear being eccentrically mounted upon the shaft, and a latch 30 carried by the external gear, and alternately engageable with the shaft and support for the purpose set forth, said latch being protectingly inclosed between said gear and said support.

11. A support, a shaft journaled therein, a drum upon the shaft having an internal gear, an external gear meshing with the internal gear, said external gear being eccentrically mounted upon the shaft, and a latch 40 carried by the external gear, and alternately engageable with the shaft and support for the purpose set forth, said internal gear being arranged at one end of the drum.

12. A support, a shaft journaled therein, 45 a drum upon the shaft having an internal gear, an external gear meshing with the internal gear, said external gear being eccentrically mounted upon the shaft, and a latch carried by the external gear, and alternately 50 engageable with the shaft and support for the purpose set forth, and additional means for locking the drum to the support.

In witness whereof, I have hereunto set my hand this 31st day of October 1925.

LEONARD D. NILSON.
